CLAIM

The ornamental design for a combined wall mounted bottle opener and cap receptacle, as shown and described.

DESCRIPTION

FIG. 1 is a front elevational view of a combined wall mounted bottle opener and cap receptacle showing my new design;

FIG. 2 is a rear elevational view thereof;

FIG. 3 is a side elevational view, the opposite side being identical thereof;

FIG. 4 is a top plan view; and

FIG. 5 is a bottom plan view.
